UNITED STATES PATENT OFFICE.

WILLIS H. GRAFFORD, OF NEBO, ILLINOIS, ASSIGNOR OF ONE-HALF TO
THOMAS J. SCRANTON, OF SAME PLACE.

WIRE-STRETCHER.

SPECIFICATION forming part of Letters Patent No. 590,885, dated September 28, 1897.

Application filed May 14, 1897. Serial No. 636,595. (No model.)

To all whom it may concern:

Be it known that I, WILLIS H. GRAFFORD, a citizen of the United States, residing at Nebo, in the county of Pike and State of Illinois, 5 have invented certain new and useful Improvements in Wire-Stretchers; and I do declare the following to be a full, clear, and exact description of the invention, such as will enable others skilled in the art to which it app-
10 pertains to make and use the same.

My invention has relation to wire-stretchers.

The object is to provide a simple, strong, and inexpensive device of this character 15 which may be easily operated and which will effectively stretch the fence-wires to take up all sag.

With this object in view the invention consists of certain features of construction and 20 combination of parts which will be hereinafter fully set forth and claimed.

In the accompanying drawings, Figure 1 is a side view of my improved wire-stretcher, and Fig. 2 is a cross-section on the line xx of 25 Fig. 1.

In said drawings, 1 denotes two supports or posts, and 2 denotes a track which is provided with sleeves 3, that are adjustably connected to the posts by set-screws 4. One of these 30 sleeves also carries bearings 5, in which is journaled an operating-wheel 6, provided with a pinion 7, which engages a rack-bar 8, mounted to slide in said track, as more clearly shown in Fig. 2. This rack-bar at one end is pro-
35 vided with a wire clamp or holder 9, which is adapted to clamp the wire to be stretched.

The periphery of the operating-wheel is provided with teeth 10, which are adapted to be engaged by a bolt 11, moving in a guide 12, 40 secured to the under side of the track.

In operation the wire to be stretched is engaged with the clamp that is carried by the end of the rack-bar, and by rotating the wheel its pinion will force the rack-bar outwardly, and thus stretch the wire. To hold the wire 45 in this stretched position, I slide the bolt into engagement with the teeth on the operating-wheel, thus locking said wheel against rotation.

By referring to Fig. 2 it will be seen that 50 the rack-bar has laterally-projecting flanges which fit within the track, the rack portion of the bar projecting up through a longitudinal slot in the track.

Although I have specifically described the 55 construction and relative arrangement of the several elements of my invention, I do not desire to be confined to the same, as such changes or modifications may be made as clearly fall within the scope of my invention 60 without departing from the spirit thereof.

Having thus described my invention, what I claim, and desire to secure by Letters Patent, is—

A wire-stretcher comprising the two up- 65 right posts attached to a base, the track 2 vertically adjustable on said posts, a rack-bar mounted to slide on said track and having a wire-clamp on a stud rising from one end thereof, the pinion and gear for sliding the 70 rack-bar, and a sliding bolt mounted in the frame and designed to engage the teeth of the operating-wheel for holding the same against rotation, substantially as described.

In testimony whereof I hereunto affix my 75 signature in presence of two witnesses.

WILLIS H. GRAFFORD.
